UNITED STATES PATENT OFFICE.

CHESTER JOSEPH GRUBER, OF ST. LOUIS, MISSOURI, ASSIGNOR OF ONE-HALF TO
NATHAN E. STEINBERG, OF ST. LOUIS, MISSOURI.

TIE.

Application filed August 9, 1926. Serial No. 123,033.

This invention relates to neckties, and the object of the invention is to provide a tie of a new and original shape that presents an attractive appearance and that may be produced economically from a minimum of material and with a minimum expenditure of time and effort. Other objects and advantages will appear in the course of the following description of a preferred embodiment of the invention.

In the accompanying drawing forming part of this specification, in which like numbers of reference denotes like parts wherever they occur,

15 Figure 1 is a plan view of the unfolded or extended strip, from which the tie is formed by folding;

20 Figure 2 is a longitudinal sectional view taken on the line 2—2 in Figure 1;

25 Figure 3 is a front view of the strip after it has been folded into tie formation;

Figure 4 is a rear view of the tie; and

30 Figure 5 is a longitudinal sectional view taken on the line 5—5 in Figure 4.

35 The strip 1 from which the tie is formed preferably comprises two superposed oblong-shaped pieces or blanks of suitable cloth or tie material 2 and 3, that are sewed together at their edges on inturned seams 4 by means of stitching 5. A strip of crinoline 6 or the like is preferably interposed between the strips 2 and 3 in order to provide ample stiffness for the strip 1 so that the latter will maintain its shape after being folded. 40 A stuffing 7 of cotton or other loose, fluffy material is, also, preferably introduced into the hollow strip prior to completely sewing together the marginal edges of the strips 2 and 3, the stuffing preferably being disposed on only one side of the crinoline 6, say on the side facing the strip 2.

45 The end portions 8 and 9 are folded over the intermediate portion 10 of the strip on respective oblique hypothetical lines 11, which may, if desired, be indicated on the strip, prior to folding, by creasing or marking in any other suitable manner, in order to facilitate folding thereon. Both end portions 8 and 9 are preferably folded over the same

50 side of the strip, say the fluffy or tufted side covered by the strip 2. The folded portions 8 and 9 are preferably, also, of such length with relation to the width of the strip that the end edges 12 project laterally

from the lateral edges 13 and 14 of the intermediate portion 10 of the strip. The oblique lines 11 are, also, preferably inclined in the same direction, so that the portions 8 and 9 extend transversely of the intermediate portion 10 in respective opposite directions. 55 The lines 11 are preferably so spaced that, when the portions 8 and 9 are doubled over the portion 10, the edge 13 of portion 8 meets the edge 14 of portion 9, and the said edges are preferably secured together 60 by stitches 15. The side shown in Figure 3 is preferably considered as being the front of the tie, while the side exhibited by Figure 4 may be considered as the rear side, and suitable attaching means, such as a conventional elastic band 16, may be sewed thereto by stitches 17. The strip 17, as will be understood, is placed around the collar of the wearer, and the hook 18 at one end thereof is hooked to the eye or loop 19 65 at the other end of the strip 17.

An inspection of Figure 3 shows that the intermediate portion 10 is of rhomboidal shape, while the end portions 8 and 9, projecting from the opposite edges 14 and 13, respectively, of the rhomboid 10, are substantially rectangular in outline. The tie, therefore, presents an artistic and attractive appearance, which may be further enhanced, if desired, by producing different decorative 70 effects on the outer sides of the strips 2 and 3. In the illustrated tie, for instance, it will be observed that the side 2 is plain, while the side 3 is decorated with light 75 polka dots 20 on a dark background, so that an artistic contrast is produced between the end portions 8 and 9 and the rhomboidal portion 10 in the folded tie, as illustrated in Figure 3. The end portions 8 and 9, also, 80 present a tufted appearance on the front 85 of the tie because of the stuffing 7 being adjacent to the strip 2.

On account of the small area of the strips 2 and 3, much scrap material is available 90 from which they can be cut, and it will be observed that the tie may be quickly and easily formed, so that the tie may be very 95 economically produced.

This tie is, also, of a new and original 100 shape. Instead of being produced from a plurality of superposed blanks, it may manifestly be formed of a single blank of material, which may have different designs

on its opposite sides. The shape may, also, be produced, without folding, by cutting the blanks to conform to the outline of the finished tie, or by cutting separate blanks 5 for the rhomboidal portion and the end portions and sewing them together to form the shape of the finished tie.

Having thus fully described this invention, I hereby reserve the benefit of all 10 changes in form, arrangement, order, or use of parts, as it is evident that many minor changes may be made therein without departing from the spirit of this invention or the scope of the following claims.

15 I claim:

1. A necktie comprising a strip having its end portions doubled over on respective oblique lines so that one lateral edge of each doubled end portion is alined with the opposite lateral edge of the other doubled end portion.
2. A necktie comprising a strip having its end portions doubled over the same side of the strip on respective oblique lines so that one lateral edge of each doubled end portion

meets the opposing lateral edge of the other doubled end portion.

3. A necktie comprising a strip having its end portions doubled over on respective oblique lines so that one lateral edge of each doubled end portion meets the opposite lateral edge of the other doubled end portion, the said meeting lateral-edge portions being secured together.

4. A necktie comprising a strip having an 35 intermediate portion and end portions that project obliquely in respective opposite directions from the ends of the intermediate portion.

5. A necktie comprising a strip having its 40 end portions doubled over the same side of the strip on respective oblique lines so that one lateral edge of each doubled end portion meets the opposing lateral edge of the other doubled end portion and attaching means 45 borne by the folded end portions.

In testimony whereof I hereunto affix my signature.

CHESTER JOSEPH GRUBER.
